TEXTILE FABRIC AND METHOD OF
KNITTING THE SAME

Edward J. Slater, Port Jervis, N. Y., assignor to
Gehring Textiles, Inc., New York, N. Y., a cor-
poration of New York, and Chantex, Inc., Port
Jervis, N. Y., a corporation of New York

Application May 6, 1950, Serial No. 160,456

12 Claims. (Cl. 66—195)

1

The present invention relates to a textile fabric and the method of knitting the same. It relates, more particularly, to a fabric knit from nylon yarn and the method of knitting such fabric.

An object of the present invention is to provide a fabric knit from yarns of nylon or similar material which has a filmy or misty appearance and a texture similar to a crepe de Chine in contrast to the smooth texture and sheer character of fabrics knit in the usual manner from such yarns. Another object of the present invention is to provide a fabric knit from nylon yarns which will drape or hang in a graceful and attractive manner when finished and which is suitable for use in articles of clothing. The filmy or misty appearance of the present fabric and its crepe-like texture make it especially desirable for use in garments such as women's blouses, bridal veils or the like and various designs may be incorporated in the fabric which also give it a novel and attractive appearance.

Other objects and advantages of the present invention will be apparent and best understood from the following description and the accompanying drawings in which:

Fig. 1 is a pictorial representation of a piece of a fabric embodying the invention; and

Fig. 2 is a diagrammatic illustration showing the construction of the fabric shown in Fig. 1 on an enlarged scale.

Referring to the drawings in detail, a fabric 20, knit in accordance with the present invention is shown in Fig. 1. The fabric 20 has a background or body portion, indicated generally at 21, and a design or pattern formed thereon by the areas indicated at 22. The design areas 22 are slightly raised with respect to the background or body 21 of the fabric and are somewhat more opaque than the surrounding portions of the background or body 21. However, the entire fabric has a crepe-like texture and a filmy or misty appearance.

In knitting the fabric 20, nylon thread or yarn of the type customarily used for knitting sheer fabrics may be employed; i. e., yarn which has not been treated or spun prior to the knitting thereof so as to change or affect the texture of the fabric knit therefrom. The fabric 20 is a flat-knit fabric and may be knit in accordance with the present invention on a two-bar knitting machine of the tricot type in which yarns or threads are knit on both sides of the fabric. Such machines are well known and their operation need not be described in detail here.

2

For clarity, the details of the manner in which the fabric 20 is knit are shown on an enlarged scale in Fig. 2, and the knitted loops of yarn are shown in an expanded condition approximating the manner in which they would appear as they are formed on the needles of the knitting machine. However, it will be understood that this illustration is diagrammatic and that when the loops are released from the needles after being knitted in accordance with the present invention, the knitted loops will be drawn together and the fabric will have a filmy transparency and a crepe-like texture.

For convenient reference, the courses of a portion of the fabric 20 shown in Fig. 2 have been identified by the reference numerals 1 through 16 along one side of Fig. 2 corresponding to one complete cycle of movement of a sixteen-move pattern wheel. The wales of the fabric 20 have been identified by the reference numerals 30 through 42, reading from left to right across the top of Fig. 2. Yarns or threads 23 indicated by the solid lines in Fig. 2, are knit in connected loops forming the wales and courses of the background or body 21 of the fabric 20. Yarns or threads 24, indicated by the broken lines in Fig. 2, are knit with the background yarns at spaced groups of wales and in spaced groups of courses forming the design areas 22 on the background.

In the illustrated embodiment of the invention, the yarns 23 for the background are fed at the back bar of the machine. These background or back-bar threads 23 are fed at each thread-feeding position of the back bar and are knit in the same manner as the customary front-bar stitch for a jersey fabric; i. e., with one needle or wale being skipped or traversed by the threads in alternate directions in succeeding courses on each move of the pattern wheel.

The threads 24 for the design areas are knit on the face of the fabric 20 and are fed at the front bar of the machine. In the illustrated embodiment, the threads 24a through 24f are fed at six thread-feeding positions of the front bar, respectively, and then are omitted for six thread-feeding positions of the front bar across the width of the fabric. By this arrangement the front-bar threads are fed and knit with the back-bar threads in spaced groups of wales. However, it will be understood that the number of thread-feeding positions of the front bar at which threads are fed in each group and the number of positions spacing the groups may be varied as desired to change the size and shape of the areas forming the pattern or design on the face of the

fabric. For example, the front-bar threads 24 may be fed at two thread-feeding positions and then be omitted for two positions; or they may be fed at three thread-feeding positions and then be omitted for the next three thread-feeding positions; or they may be fed at four thread-feeding positions and then be omitted for the next four thread-feeding positions.

The front-bar threads 24a-24f are each knit in a similar manner. Thus, for brevity, the manner in which one of these threads is knit will be described hereinafter and it will be understood that this description will also apply to the other front-bar threads.

Starting at the first position of the pattern wheel (see the lower part of Fig. 2), the front-bar thread 24a is knit with the background thread 23 at wale 32 in course 1 of the fabric. At the second position of the pattern wheel, the front-bar thread 24a traverses one wale 31 to the left (in a direction opposite to the back-bar thread) and is knit at an alternate wale 30 in course 2 of the fabric. At the third position of the pattern wheel, the thread 24a traverses the previously traversed wale 31 to the right and is knit at the first wale 32 in course 3. For the following five moves or positions of the pattern wheel, the front-bar thread 24a is floated across the five courses 4, 5, 6, 7, and 8. In addition to being floated across these courses, the thread 24a is traversed three wales 33, 34, and 35 to the right and at the ninth position of the pattern wheel, the thread 24a is knit at wale 36 in course 9 of the fabric. At the tenth position of the pattern wheel, the thread 24a traverses one wale 35 to the left and is knit at wale 34 in course 10. At the eleventh position of the pattern wheel, the thread 24a traverses the one wale 35 to the right and is knit at the wale 36 in course 11. Thus, the yarns 24 are knit with the background yarns in spaced series of courses and at groups of wales in each series of courses which are offset with respect to the wales at which said threads are knit in the preceding series of courses.

At the next five positions of the pattern wheel, the front-bar thread 24a is floated across courses 12, 13, 14, 15, and 16 and is traversed three wales 33, 34, and 35 to the left on the next five moves of the pattern wheel. This completes one cycle of operation of the sixteen-move pattern wheel and returns the thread 24a to the wale 32 at which it was knit in course 1. At the first position of the pattern wheel in the next cycle, the front-bar thread 24a will again be knit at the wale 32 and thereafter the above procedure is repeated. Thus, the front-bar threads 24 extend diagonally in alternate directions between the offset series of courses along the length of the fabric.

The arrangement of the pattern wheel may also be changed to vary the number of courses in each series of courses or to vary the spacing of the series of courses in which the front-bar threads 24 are knit. However, it is important that this arrangement be such that for each cycle of the pattern mechanism or repetitive portion of the design in the fabric that the normal length of the front-bar threads 24 should be less than half and preferably one-quarter the normal length of the background threads in a given length of fabric. This results in the loops of the fabric being drawn together and gives the fabric its misty or filmy appearance and crepe-like texture.

In the particular fabric illustrated and described herein, the front-bar threads 24 are fed under tension and elongated to such an extent that their normal length bears a ratio in the neighborhood of one to four with respect to the length of the threads 23 fed at the back bar in a given length of the knitted fabric. This does not mean that the front-bar threads are necessarily elongated to four times their normal length during the knitting of the fabric, but takes into account the front-bar threads being floated over a number of the courses for each cycle of the pattern wheel. By actual measurement, the length of each of the front-bar threads 24 that is fed for one cycle of the sixteen-move pattern wheel is from fourteen to sixteen inches and the length of each of the back-bar threads 23 that is fed for each cycle is fifty-six inches which is in the ratio of approximately one to four and the front-bar threads 24 are floated over ten courses in each sixteen courses of the fabric.

The feeding of the front-bar threads 24 in this relation to the back-bar threads 23 may be accomplished by suitable adjustment of the tension on the front-bar threads as they are fed. The inherent resiliency of elasticity of ordinary nylon yarns permit them to be stretched to meet the above requirements as they are being knit and make them particularly suitable for this purpose.

As previously mentioned, the difference in the lengths of the front-bar threads 24 and the back-bar threads 23 causes the wales and the courses of the fabric to be drawn together when it is released from the needles and produces a marked effect on the sheerness and texture of the fabric. It not only gives the fabric a filmy or misty appearance, but is also gives the fabric a crepe-like texture or feel. Contrary to what might be expected, this drawing of the stitches together does not interfere with the manner in which the fabric drapes or hangs when suitably finished, but conversely gives the fabric a better body and handle so that it hangs and drapes more gracefully than it otherwise would.

It will be understood that various modifications and changes may be made in the embodiment of the invention illustrated and described herein without departing from the scope of the invention as defined by the claims appended hereto.

I claim:

1. A knit nylon fabric having a filmy transparency and a crepe-like texture comprising threads knit in connected loops forming wales and courses of a background, and threads knit with the background threads at spaced groups of wales in spaced series of courses of the background and floated across courses intervening between the respective series of courses, the number of said intervening courses being at least equal to the number of courses in each series and the normal length of said second-mentioned threads being less than half the length of the background threads knit in all of said courses.

2. A fabric knit of nylon threads which has a filmy transparency and a crepe-like texture comprising nylon threads knit in connected loops forming wales and courses of a background, and nylon threads knit with said background threads at spaced groups of wales in a series of courses of the background, said last-mentioned threads being floated diagonally across a number of wales and courses to a second group of wales

and a second series of courses of the background at which said threads are knit, said second series of courses being spaced from the first series of courses, the normal length of said second-mentioned threads knit in the first series of courses and extending to the second series of courses being less than half the normal length of the background threads knit in all of said courses.

3. A fabric knit of nylon threads which has a filmy transparency and a crepe-like texture comprising threads knit in connected loops forming wales and courses of a background, and threads knit with said background threads at spaced groups of wales in three consecutive courses of the background, said last-mentioned threads being floated diagonally across three wales and five courses to a second series of three consecutive courses at which said second-mentioned threads are knit, the normal length of said second-mentioned threads knit in the first series of three courses and floated across the five courses being in the neighborhood of one-quarter the normal length of the background threads knit in all of said courses.

4. A fabric knit of nylon threads which has a filmy transparency and a crepe-like texture comprising threads knit in connected loops forming wales and courses of a background, and threads knit with said background threads at spaced groups of wales in three consecutive courses of the background, said last-mentioned threads being floated diagonally in one direction across three wales and five courses to a second series of three courses at which said threads are knit and then being floated diagonally in the opposite direction across three wales and five courses to the first-mentioned groups of wales in a third series of three courses, the normal length of said second-mentioned threads knit in and floated between said series of courses being in the neighborhood of one-quarter the normal length of the background threads knit in all of said courses.

5. A knit fabric of the tricot type having a filmy transparency and a crepe-like texture wherein threads of a resilient material such as nylon are knit on both sides of the fabric comprising threads knit on one side of the fabric in connected loops forming wales and courses in the fabric, said threads traversing one wale in opposite directions in successive courses of the fabric, and threads knit with said background threads on the other side of fabric, said second-mentioned threads being knit at spaced groups of wales in spaced series of consecutive courses of the fabric and being floated across a number of courses intervening between the respective series of consecutive courses, the length of said second-mentioned threads knit in said series of consecutive courses and floated over the intervening courses being less than one-half the length of the first-mentioned threads knit in all of said courses.

6. A knit fabric of the tricot type having a filmy transparency and a crepe-like texture as defined in claim 5 wherein the second-mentioned threads traverse one wale in a direction opposite to the direction in which the first-mentioned threads traverse in the series of consecutive courses in which said first-mentioned threads are knit.

7. A knit fabric of the tricot type having a filmy transparency and a crepe-like texture as defined in claim 5 wherein the second-mentioned threads traverse one wale in a direction opposite to the direction in which the first-mentioned threads traverse in the series of consecutive courses in

which said first-mentioned threads are knit and said second-mentioned threads are floated diagonally in alternate directions across a number of wales between the respective series of consecutive courses in which said second-mentioned threads are knit.

8. The method of knitting a flat fabric which includes the steps of feeding and knitting threads on one side of the fabric at all of the needles in 10 connected loops forming wales and courses of the fabric, and simultaneously feeding and knitting threads of a resilient material such as nylon on the other side of the fabric at spaced groups of needles in spaced series of courses and floating 15 said last-mentioned threads across courses intervening between said series of courses, said last-mentioned threads being fed at one-fourth the rate at which said first-mentioned threads are fed.

9. The method of knitting a flat fabric comprising the steps of feeding and knitting threads on one side of the fabric in connected loops forming wales and courses in the fabric, and simultaneously feeding and knitting threads of a resilient material such as nylon on the other side 20 of the fabric at spaced groups of needles in spaced series of courses and floating said last-mentioned threads across courses intervening between said spaced series of courses, said last-mentioned threads being traversed in opposite directions across a number of wales between the alternate 25 series of courses in which said threads are knit and being fed at one-fourth the rate at which said first-mentioned threads are fed.

10. The method of knitting a flat fabric which 30 includes the steps of feeding and knitting threads on one side of the fabric at all of the needles in connected loops forming wales and courses of the fabric, and simultaneously feeding and knitting threads of a resilient material such as nylon on the other side of the fabric at spaced groups of needles in spaced series of courses and floating 35 said last-mentioned threads across courses intervening between said series of courses, said last-mentioned threads being fed at less than one-half the rate at which said first-mentioned threads are fed.

11. A knit fabric having a filmy transparency and a crepe-like texture comprising threads of 40 nylon knit in connected loops, said loops forming a background having wales and courses running throughout the fabric, and nylon threads knit with the background threads at spaced groups of wales and in spaced series of courses, said last-mentioned threads being floated across the face 45 of the background between each series of courses in which said last-mentioned threads are knit and forming design areas on the background, the length of said last-mentioned threads being less than half the length of the background threads 50 in the fabric.

12. A flat-knit fabric having a filmy transparency and a crepe-like texture which comprises a background consisting of nylon threads knit in 55 connected loops forming wales and courses running throughout the fabric, said background being normally sheer and transparent in appearance and design areas formed on one face of said background, said design areas consisting of nylon threads knit with the background threads in spaced groups of wales and in spaced series of courses of the background and being floated 60 across the face of the background between said spaced series of courses, the total length of said 65 design area threads being approximately one- 70 75

fourth the length of the background threads forming the fabric.
